DESIGN FOR A DRAWER PULL OR SIMILAR ARTICLE

Otto E. Uhlmann, Grand Rapids, Mich., assignor to Keeler Brass Company, Grand Rapids, Mich.

Application December 30, 1935, Serial No. 60,333

Term of patent 3½ years

To all whom it may concern:

Be it known that I, Otto E. Uhlmann, a citizen of the United States, residing at the city of Grand Rapids, in the county of Kent and State of Michigan, have invented a new, original, and ornamental Design for a Drawer Pull or Similar Article, of which the following is a specification, reference being had to the accompanying drawing,
forming a part thereof.

Fig. 1 is a front view, and
Fig. 2 is a side view of a drawer pull showing my new design.

I claim:

The ornamental design for a drawer pull or similar article as shown.

OTTO E. UHLMANN.
